BY
Chesley S. Barr
ATTORNEY

UNITED STATES PATENT OFFICE.

LUTHER J. KINNARD, OF CHICAGO, ILLINOIS, ASSIGNOR TO KAESTNER AND HECHT ELEVATOR COMPANY, A CORPORATION OF ILLINOIS.

AUTOMATIC GATE CLOSER.

Application filed March 15, 1928. Serial No. 261,825.

My invention relates to door-and-gate-closing systems and has particular reference to closures for elevator doors and gates.

An object of my invention is to provide a control system for automatically causing the doors and gates used with elevator systems to be closed at such times as the elevator is in condition to be moved.

Another object of my invention is to provide a control system for elevator doors and gates wherein the gates or doors, when opened, will remain open for a predetermined length of time only.

Another object of my invention is to provide a control system for elevator gates wherein, if the gate is opened at any time when the elevator is not standing adjacent a hatchway door, it will be immediately closed.

Another object of my invention is to provide a control system for elevator gates wherein, when the elevator is adjacent to a hatchway door and the gate is opened without the door being opened, the gate will remain open for not longer than a predetermined length of time.

Another object of my invention is to provide a control system for elevator gates wherein, when the elevator is positioned adjacent to one of the hatchway doors and the gate is opened, it will be held open and the subsequent opening and reclosing of the door will permit the gate to close immediately.

Modern elevator systems require a gate on the elevator car, which gate is usually of the collapsible open-work metal type arranged for operation by an attendant on the elevator car, or by the passengers on the car. This gate is usually independent of the doors or closures provided for the hatchway at each of the several floors or landings past which the elevator moves.

The safe operation of elevators requires that both the doors and the gates should be closed at all times that the elevator car is moving in the hatchway. Hence, it is the usual practice to provide a switch which is operated only when the gate is in completely closed position for permitting current to be supplied to the elevator motor and permitting the elevator to move only when the gate is closed.

When the elevators are of the type requiring an attendant or operator upon the car, it is the usual practice for the attendant to manually open the gate and to hold the same open

during such times as the elevator car is positioned adjacent to one of the hatchway doors for the purpose of discharging or receiving passengers. The gates are usually biased by means of a spring which tends to close the gate upon release thereof by the attendant.

However, in push-button elevator systems, that is, the type wherein the movements of the elevator car are controlled by the passengers rather than by an attendant, the practice has been to provide no biasing device to close the gate but to depend upon the thoughtfulness of the passengers for insuring that the gate shall be closed when they leave the car, and, hence, that the car is in condition to respond to calls by other persons. This is unsatisfactory since any negligence of the passengers to close the gate renders the system inoperative until some one closes the gate.

To overcome this condition, a biasing spring may be provided but, if this done, it is necessary that a person entering or leaving the car shall hold the gate in its open position against the force of the biasing spring. This operation becomes inconvenient when the passengers have their arms and hands encumbered by bundles or other impedimenta.

Hence, it is desirable that some means should be provided for temporarily holding the gate in an open position against the biasing force of the spring. On the other hand, this temporary holding of the gate should not be unduly prolonged, that is, prolonged beyond the time during which the holding is absolutely necessary, and in addition to this, it is desirable that such holding of the gate in an open position should not be effective at such times as the gate, if opened, renders elevator operation unsafe or causes a stopping of the elevator at any place other than adjacent to one of the hatchway doors.

I propose, therefore, to provide a holding device for temporarily retaining the door in open position only at such times and under such conditions as stated above.

My system will be described with reference to the accompanying drawing wherein the sole figure is a diagrammatic view illustrating an elevator gate provided with a spring closing means and illustrating the manner in which a holding device is controlled in accordance with the position and operative condition of the elevator car and the hatchway doors.

Referring to the drawings, I have illustrated an elevator car C suspended upon a cable Ca which passes over a hoisting drum (not shown). The elevator car C operates in a hatchway (not shown) provided with doors at each of the floor levels past which it moves. Three doors are illustrated as associated with three floors and are designated by the reference characters D¹, D² and 10 D³, respectively.

The lower portion of the drawing illustrates, in some detail, the collapsible gate G carried by the elevator car C. This gate is illustrated as of a well-known type, constructed of vertical strips 1 and loosely mounted angular cross members 2 so arranged as to permit the gate to be expanded to completely close the opening between the respective sides 3 and 4 of the elevator car. The 15 gate is suspended from a trackway 5 upon which rollers 6 are suitably mounted for reducing the friction between the gate and the trackway when the gate is to be moved. A toggle lever 7, comprising links 8 and 9, is 20 provided for moving the gate to a closed position. The link 9 is suitably pivotally secured to a stationary support 10 mounted upon the elevator car C. A compression spring 11 is so mounted upon the elevator car, 25 as by means of a bracket 12, as to exert a force tending to move a rod 13 to the right. The rod 13 is pivotally connected to the link 9 by a short link member 14. Hence, the force of the spring 11 is exerted against the link 9, 30 tending to straighten the toggle joint 7 and to force the gate to a closed position.

An extension 15 of the rod 13 is suitably supported for reciprocating movement within a bracket 16, thus placing the extension 15 40 in a position to be engaged by a cam member 17, normally biased by gravity to a position engaging the extension 15 but movable to a released position upon the energization of a releasing electromagnet 18. The bracket 16 45 is suitably mounted upon the elevator car, preferably adjacent to the bracket 12 and the spring 11.

Since it is desirable that the doors or closures for the hatchway should be in closed 50 position at all times when the elevator car is moving, or is in condition to move, suitable doorswitches 19, 20 and 21 are associated with the doors D¹, D² and D³, respectively. These switches 19, etc., are so arranged in the circuit 55 for a relay 22 that, upon closing of all of the doors, relay 22 is energized. Relay 22, when energized, preferably completes the circuit supplying current to the elevator motor. This relay is one which is usually provided in elevator control systems and it has not been deemed necessary to illustrate the motor-control circuits actuated thereby beyond indicating a possible connection of the motor-circuit-controlling devices as set forth herein- 60 after.

Since it is desirable that the gate should not be held open except when the car is adjacent to one of the hatchway doors, I have provided a control system for the releasing magnet 18 which includes suitable floor switches F¹, F² and F³ associated with the first, second and third floors, respectively, which switches may be of any suitable type operable only when the elevator car C is adjacent to the associated hatchway door. I have illustrated the 70 switches F¹, F² and F³ as operable by means of a cam FC carried by the car C, which cam will engage the switches and move the same to open position as the car approaches the associated floor level. It is to be understood, however, that these switches or substitutes therefor may be provided upon a floor selector, such as is usually employed to control the operation of push-button elevators or to control the signal systems usually associated with the elevators. 80

Switches F¹, F² and F³ are illustrated as being of the normally closed type having their contact members in series relation in a circuit which controls the energization of a 90 relay 24.

To provide the necessary time interval during which the gate is to remain open, I have provided a relay 25 provided with a dash-pot 26 or other suitable retarding means 95 which will prevent the contact members of this relay from being moved to a closed position for a predetermined length of time after the energization of the relay coil, but will permit the relay contact members to open immediately upon deenergization of the coil. When relay 24 has been actuated, it is desirable (as will be set forth hereinafter) to maintain the circuit to relay 25 and, for this purpose, I have provided a holding relay 27. 100

A relay 28, having its operating coil in circuit with a switch 29 operable to position only when the gate G is in its closed position, is provided to prevent the continuous energization of releasing magnet 18 while the gate G 110 is closed.

The operation of my system may best be understood by reference to an assumed operation. Assuming that the elevator car is approaching the first floor preparatory to stopping thereat, and, if persons on the car attempt to open the gate G prior to the time that the cam FC engages and operates floor switch F¹, it will be observed that relay 24 will be in closed-circuit position, since all hatchway doors are closed. The opening of the car gate G opens the circuit for relay 28 at gate switch 29, and a circuit will be completed for supplying current to the releasing magnet 18 for the friction clutch 17, hence, the clutch 17 will be withdrawn from engagement with the rod 15, and the gate, upon release by the person, will be immediately closed by the expansion of spring 11. 120

The energizing circuit for releasing mag- 130

net 18 just described extends from line conductor L^1 , through conductors 40 and 41, contact members of relay 28, conductor 42, contact members a of door relay 22 (now in circuit closing position since all of the doors D^1 , D^2 and D^3 are in closed position), conductors 43 and 44, contact members of relay 24, conductor 45, the coil of releasing magnet 18 and conductors 46, to line conductor L^2 .

Thus, it will be observed that, if any attempt is made to open the gate during such time as the elevator car is moving or is standing at any point in the hatchway except adjacent to one of the hatchway doors, with the cam FC engaging and operating one of the floor switches, the car gate will upon being released immediately be reclosed.

Assuming, however, that the car moves into position adjacent to the door D^1 , and the floor switch F^1 is moved to its open-circuit position, relay 24 will be deenergized and will open its contact members, hence, with relay 24 open, subsequent opening of the car gate G, causing deenergization of relay 28, will not complete a circuit for releasing magnet 18 and, upon movement of the gate to open position, the friction clutch 17 will engage and hold the gate in such position.

Deenergization of relay 28, however, closes a circuit for actuating timed relay 25, which circuit extends from line conductor L^1 , through conductors 40 and 41, contact members of relay 28, conductor 42, contact members a of door relay 22, conductors 43 and 47, the coil of timed relay 25 and conductor 48, to line conductor L^2 . Relay 25 starts moving to closed-circuit position, retarded however, by the influence of dashpot 26 which may be adjusted to give any desirable time element during which the passengers will have an opportunity to open the hatchway door.

It has been observed that approximately 10 seconds is a sufficient length of time to permit a passenger within the car to open the door but it is to be remembered that this time may be varied to suit the conditions pertaining to any particular elevator installation.

Assuming, for example, that the person opening the car gate discovers that he does not desire to leave the car at the first floor but wishes to travel to some other floor and thus does not open the car door D^1 , it will be observed that, after the lapse of the time determined by the dash-pot 26, a circuit will be completed for releasing magnet 18, which circuit extends from line conductor L^1 , through conductors 40 to 43, as previously traced, and thence, by way of conductor 49, contact members of relay 25, conductors 50, 62 and 45, releasing magnet 18 and conductor 46, to line conductor L^2 . Hence, the gate G

will be maintained open by the friction clutch 17 only until the expiration of the predetermined time allowed to permit the passenger to open the hatchway door.

On the other hand, it is proposed that the force exerted by the friction clutch 17 will only be sufficient to hold the gate against the force of spring 11, hence, the passenger may, if he desires, force the gate to closed position before the release of clutch 17.

Assuming, on the other hand, that the passenger, desiring to leave the car at the first floor, opens hatchway door D^1 , it will be observed that the opening of door D^1 breaks the circuit for relay 22 at door switch 19. Relay 22, therefore, opens its contact members a and closes its contact members b . The opening of contact members a of relay 22 prevents energization of the releasing magnet at the expiration of the predetermined length of time since the circuit for timed relay 25, as previously traced, extended through the contact members a of relay 22.

The closing of contact members b of relay 22 completes a circuit for maintaining relay 27, which circuit extends from line conductor L^1 , through conductors 40 and 51, contact members b of relay 22, conductor 52, the coil of relay 27 and conductor 53, to line conductor L^2 . Maintaining relay 27, when energized, closes its contact members a , completing a holding circuit for itself, extending from line conductor L^1 through conductors 40, 41, 42 and 54, contact members a of relay 27 to the coil of relay 27, and thence by way of conductor 53 to line inductor L^2 .

Relay 27 also closes its contact members b , partially completing a circuit for energizing releasing magnet 18, which circuit, however, is open at contact members a of door relay 22.

Assuming now that the passenger leaves the elevator car C, without being required to hold the car gate G open, and then recloses the hatchway door D^1 , relay 22 will be energized upon the closure of door switch 19 by way of the circuit which extends from line conductor L^1 through conductor 57, door switches 21, 20 and 19 in series relation, respectively, conductor 58, the coil of relay 22 and conductor 59 to line conductor L^2 . The energization of relay 22 completes the circuit partially closed by relay 27 and supplies current to releasing magnet 18 by way of a circuit which extends from line conductor L^1 , through conductors 40, 41 and 42, contact members a of relay 22, conductors 43 and 60, contact members b of relay 27, conductors 61, 62 and 45 to releasing magnet 18 and conductor 46, to line conductor L^2 . Releasing magnet 18, therefore, moves the clutch member 17 from engagement with rod 15 and the gate will be closed by spring 11.

It will be observed that, if a greater length

of time than the 10 seconds allowed by relay 25, is consumed by the passenger in moving from the elevator car C, the gate G will be maintained in open position until the passenger has not only left the car but has re-closed the hatchway door and that, thereafter, the gate G will be immediately closed. Hence, there is no loss of time between the exit of the passenger and the conditioning of the elevator car to proceed in answer to any other calls which may be awaiting elevator service.

While it has not been deemed necessary to show the complete circuits controlled by the gate relay 28 and the door relay 22 for preventing operation of the elevator car C, it will be obvious to persons skilled in the elevator art that the motor-control circuits may be suitably controlled by these relays to prevent operation of the elevator car at any time when either the gate G or the doors D¹, D² and D³ are in open position. I have diagrammatically illustrated such connection by the arrow-head 65 indicating the point of connection of the coil of a suitable line switch, such as is usually provided in elevator-motor-control systems.

It will be observed, therefore, that I have provided a control system for insuring the closure of the gates and doors at all times when it is desired that the elevator car should be caused to move and that I have provided a system for insuring closure of the car gate regardless of the neglect or carelessness of persons using the car, to make sure that the car gate is completely closed when they leave the car. In addition to this, it will be observed that I have provided a system by means of which, whenever the car is so positioned as to permit entrance and exit of passengers, the car gate will be maintained in an open position without the necessity of the gate being forcibly held in this position by the passengers desiring to board or leave the car.

While the disclosed embodiment of my invention appears to be in the preferred form, it is to be understood that the description is illustrative only, and I do not desire to be limited to any of the details shown and described herein except as defined in the appended claims.

I claim as my invention:—

1. In an elevator system, an elevator operable past a plurality of floors, a closure for said elevator, means biasing said closure to closed position, means operable when said closure is opened for maintaining said closure open against the effect of said bias, and means operably responsive to the position of said elevator for rendering said maintaining means effective only when said elevator is adjacent to any one of said floors.

2. In an elevator system, an elevator operable past a plurality of floors, a closure for

said elevator, means biasing said closure to closed position, means operable when said closure is opened for maintaining said closure open against the effect of said bias, and means operably responsive to the position of said elevator for rendering said maintaining means effective only when said elevator is substantially level with any one of said floors.

3. In an elevator system, an elevator operable in a hatchway past a plurality of floors, a closure for said hatchway at each of said floors, a closure for said elevator, means biasing said elevator closure to closed position, means operable by opening said elevator closure for maintaining said elevator closure in open position, and means for rendering said maintaining means ineffective after the lapse of a predetermined time after said elevator closure is opened, and means operable by opening of the hatchway closure for rendering said last named means ineffective.

4. In an elevator system, an elevator operable in a hatchway past a plurality of floors, a closure for said hatchway at each of said floors, a closure for said elevator, means biasing said elevator closure to closed position, means operable by opening said elevator closure for maintaining said closure in open position, and means for rendering said maintaining means ineffective after the lapse of a predetermined time after said elevator closure is opened, and means operable by opening of the hatchway closure for rendering said last named means ineffective and operable by the reclosing of said hatchway closure for releasing said maintaining means.

5. In an elevator system, an elevator operable in a hatchway past a floor, a closure for said hatchway, a closure for said elevator, means biasing said elevator closure to closed position, means operable when said elevator closure is in open position for maintaining said closure in said position and means operable by opening and closing the hatchway closure for releasing said maintaining means.

6. In an elevator system, an elevator operable past a plurality of floors, a gate therefor, and means for insuring closure of said gate comprising means biasing said gate to closed position, releasable means for holding said gate in open position, when so moved, and timed means, initiated by opening said gate, for releasing said holding means at a predetermined time thereafter.

7. In an elevator system, an elevator operable past a plurality of floors, a gate therefor, and means for insuring closure of said gate comprising means biasing said gate to closed position, releasable means for holding said gate in open position when so moved, and timed means, initiated by opening of said gate, for releasing said holding means at a predetermined time thereafter and means operably responsive to the position

of said elevator for rendering said holding means effective only when said elevator is adjacent to a floor.

8. In an elevator system, an elevator operable in a hatchway past a plurality of floors, a gate for said car, a closure for said hatchway at each of said floors, means biasing said gate to closed position, means for holding said gate in open position when so moved, 10 means for releasing said holding means, and means operable by movement of any of said hatchway closures for preventing actuation of said releasing means while said closure is open.

15 9. In an elevator system, an elevator operable in a hatchway past a plurality of floors, a gate for said car, a closure for said hatchway at each of said floors, means biasing said gate to closed position, means for holding said gate in open position when so moved, 20 timed means for releasing said holding means at a predetermined time thereafter, and means operable by movement of any of said hatchway closures for preventing actuation 25 of said releasing means while said closure is open.

10. In an elevator system, an elevator operable in a hatchway past a plurality of floors, a gate for said car, a closure for said 30 hatchway at each of said floors, means biasing said gate to closed position, means for holding said gate in open position, when so moved, timed means for releasing said holding means at a predetermined time thereafter, 35 and means, operable by movement of any of said hatchway closures, for preventing actuation of said releasing means while said closure is open, and means for rendering said holding means effective only when said 40 elevator is adjacent one of said floors.

11. In an elevator system, an elevator car, a closure for said car, means biasing said closure to closed position, and means for holding said closure in open position, when 45 so moved, of sufficient power to prevent closing of said closure by said biasing means unless assisted by extraneous application of force.

12. In an elevator system, an elevator car,

a closure for said car, means biasing said 50 closure to closed position, and friction means for holding said closure in open position, when so moved, of sufficient power to prevent closing of said closure by said biasing means unless assisted by extraneous application of 55 force.

13. In an elevator system, an elevator car, a closure for said car, means biasing said closure to closed position, friction means for holding said closure in open position, when 60 so moved, of sufficient power to prevent closing of said closure by said biasing means unless assisted by extraneous application of force and means for releasing said friction means.

14. In an elevator system, an elevator car, operable in a hatchway past a plurality of floors, a closure for said car, a closure for said hatchway at each of said floors, means normally biasing said car closure to closed 70 position, means for holding said car closure in open position when so moved, releasing means for said holding means, a switch actuated by opening of said car closure for actuating said releasing means, a switch operably responsive to the movement of said car in said hatchway for preventing actuation of said releasing means by said car-closure-actuated switch only when said car is adjacent to one of said hatchway closures, timed 80 switch means initiated by said car-closure-switch means for actuating said releasing means at a predetermined time thereafter, switch means operated by movement of any of said hatchway closures from closed position, for rendering said timed switch ineffective, and a maintaining switch actuated by the hatchway-closure switch for transferring the control of said releasing means from said car-closure-actuated switch and 85 said timed switch to said hatchway-closure switch, whereby reclosing of said hatchway closure actuates said releasing means.

In testimony whereof, I have hereunto subscribed my name this eighth day of 95 Mar., 1928.

LUTHER J. KINNARD.
